CLAIM

The ornamental design for a scissors handle, as shown and described.

DESCRIPTION

FIG. 1 is a perspective view of a scissors handle showing my new design, together with an outline in broken line of the blades and pivot pin of a pair of scissors with which the scissors handle might be used, the material shown in broken line forming no part of the claimed design;

FIG. 2 is a view of the handle, blades, and pivot pin shown in FIG. 1, rotated 180° about an imaginary longitudinal central axis of the pair of scissors blades, from the position shown in FIG. 1;

FIG. 3 is a top plan view of the handle shown in FIG. 1;

FIG. 4 is a left side elevational view thereof, the right side being a mirror image thereof;

FIG. 5 is a bottom plan view thereof;

FIG. 6 is a front, or blade end elevational view thereof; and,

FIG. 7 is a rear end view thereof.
